UNITED STATES PATENT OFFICE.

FRANK SOMMER, OF BRONAUGH, MISSOURI.

STEAM-BOILER.

SPECIFICATION forming part of Letters Patent No. 459,463, dated September 15, 1891.

Application filed March 2, 1891. Serial No. 383,444. (No model.)

To all whom it may concern:

Be it known that I, FRANK SOMMER, of Bronaugh, Vernon county, Missouri, have invented certain new and useful Improvements 5 in Steam-Boilers, of which the following is a full, clear, and exact description, reference being had to the accompanying drawings, forming part of this specification.

My invention relates to steam-boilers to be 10 used for supplying steam under pressure to engines for steam-heating and for various other purposes; and the objects of my invention are to produce a boiler which shall be non-explosable and highly economical in the 15 use of both water and fuel and which shall also be stronger and more durable than any boilers heretofore produced. Furthermore, to produce a boiler which shall not be liable to burn out and other injury due to the presence 20 of sediment and which shall present a large surface to the action of the furnace.

To the above purposes my invention consists in certain peculiar and novel features of construction and arrangement, as hereinafter 25 described, and pointed out in the appended claims.

In order that my invention may be fully understood, I will proceed to describe it with reference to the accompanying drawings, in 30 which—

Figure 1 is a front elevation of my improved steam-boiler, the front wall of the setting being removed. Fig. 2 is a transverse vertical section of the same on the line 2 2 of 35 Fig. 1, the inlet-pipe 14 being shown at 14^a as partially broken away to expose the outlet-pipe 14^a to view. Fig. 3 is a longitudinal section of the boiler on the line 3 3 of Fig. 2. Fig. 4 is a detached perspective view of one 40 of the water-tubes and its inclosed fuel or fire tube.

In the said drawings, 1 designates the setting or masonry work in which the boiler is placed. As shown in the drawings, this casing is of a general rectangular form, inclosing in its upper part a chamber 2 for the boiler and having in its lower part an ash-pit or furnace-chamber 3. This precise form of the casing or setting is that which is found 45 most advantageous; but such changes as particular location of the boiler may make desirable may be made without departing from

the essential spirit of the invention. In the lower part of the front wall of the setting is placed a fire-door opening 4, and just below said opening an ash-pit door 5, while a bridge-wall 6, extending across the bottom of the setting and forming the rear wall of the ash-pit, is provided with a draft-opening 7. The middle portion 8 of the rear wall of the setting is 55 inclined downwardly, as shown, to receive the rear portion of the boiler, to be hereinafter described, and a draft-chamber 22 extends through the point of juncture of the lower portion 8 with the upper end of the portion 65 12 of the wall. A grate 9, of any suitable or preferred type, is located directly above the ash-pit 3 and supplies the heat for generating steam in the boiler, as will be presently explained. 70

My improved steam-boiler is composed of a lower chamber 10 and the upper chamber 11, constituting water-chambers, and each extending horizontally across the setting from side to side thereof in the lower and upper 75 parts thereof, respectively. These chambers are of malleable iron or boiler-iron, and each is preferably of approximately oblong rectangular form, and is inclosed upwardly from front to rear, as shown. The front edge of 80 the lower chamber 10 is supported upon the bridge-wall 6, while the rear edge is supported in the front of the rear wall of the setting at the juncture of the inclined portion 8 with the vertical lower portion 12 of the back of the setting. The front edge of the upper chamber 11 is supported upon the upper part of the front wall of the setting 1, adjacent to the stack-opening 21, to which the uptake 21^a is applied, while its rear portion is supported upon the 85 upper end of the inclined portion 8, the upper end of the said inclined portion protruding into the boiler-chamber 2 of the setting sufficiently to properly support this portion of the upper casing 11. The boiler as a whole thus 90 occupies an inclined position of about fifteen or twenty degrees, for a purpose to be presently explained. The front wall of the lower chamber 10 is formed with a man-hole, which is normally hermetically closed by a suitable 95 cover 13, and by removing which access can be had to the interior of the boiler for cleaning the same with a suitable scraper. A pipe or tube 14 is connected at its rear end to the

front wall of the chamber 10, and extends thence horizontally forward through the ash-pit immediately below the grate and also through the adjacent lower part of the front 5 wall of the setting 1. At its outer end this pipe is provided with a suitable valve 15, and the pipe serves as the means for emptying the boiler of water when said boiler is to be cleaned or inspected. The upper chamber 10 10 is provided with a suitable steam-dome 16, which is connected to the upper rear portion of the said chamber, preferably at or near its mid-length, and which protrudes upward through a suitable aperture in the top of the 15 setting 1. The usual steam-supply pipe is connected to the dome 16, and thus live dry steam is supplied to the engine or other apparatus in which the steam is to be used. The lower chamber 10 is connected with the 20 upper chamber 11 by a number of water-tubes 17, the lower ends of which are riveted to the upper side or top of the lower chamber 10, while their upper ends are similarly connected to the under side or bottom of the 25 upper chamber 11. These water-tubes thus establish communication between the interiors of the two chambers 10 and 11 and permit a free circulation of water through the boiler. Within each of these water-tubes 17 is 30 closed a flue 18, extending longitudinally through said water-tubes, and attached each at its lower end to the bottom of the lower chamber 10. The upper end of each of these flues is similarly connected to the top of the 35 upper casting or chamber 11, and it will thus be seen that each flue extends through the lower and upper chambers 10 11, and is open both at its lower and upper ends. The heat and other products of combustion first come 40 into contact with the outer surfaces of the water-tubes 17, so as to heat the water therein, and the return draft then flows backward through the channel 22 and the opening 7, and thence upward through the flues 18 and 45 imparts additional heat within to the water in the tubes 17. In order to insure a more thorough circulation of the water through the boiler, a pair of water-tubes 19, preferably of less diameter than the tubes 17, is arranged 50 as shown. The upper ends of these tubes 19 are connected together by an inverted - U bend or return, and their lower ends extend into the interior of the lower chamber 10. A water supply or inlet pipe 14^a is connected at 55 its inner end by a bend 14^b to the lower end of one of the pipes 19, and extends thence outward beneath the grate 9. Thus the water will enter through the pipe 14^a and bend 14^b and flow upward through one of the pipes 19, 60 through the bend 20, and thence downward through the companion pipe 19 and into the interior of the boiler. The water-circulation

is thus greatly facilitated and the feed-water is highly heated before entering the boiler.

From the above description it will be seen 65 that I have provided a simple and durable steam-boiler, in the operation of which the maximum degree of heat is utilized, and in which also a constant and rapid circulation of water is insured, thereby producing a full 70 and constant head of steam. There is no possibility of explosion, as the water is always in the tubes 17, and there is no danger of burning out the boiler because the heat first strikes the upper chamber and tubes. The boiler is 75 virtually self-cleaning, and is extremely economical both in use of water and fuel.

Having thus described my invention, what I claim as new therein, and desire to secure by Letters Patent, is—

80

1. An improved steam - boiler comprising an upper and a lower water-chamber, a pair of water-tubes, one of said tubes opening at its lower end into the upper part of the lower chamber and both of said tubes entering the 85 upper chamber, a pair of elbows connecting the upper ends of the tubes, and a water-supply pipe connected to the lower end of one of the tubes at a point within the lower chamber, substantially as set forth.

90

2. An improved steam-boiler comprising a suitable setting or casing, a bridge-wall located in the bottom of said setting and provided with a draft-opening below the grate, a grate supported partially above said bridge-wall, and an inclined boiler composed of an upper and lower water-chamber and heating-flues connecting and passing through said chamber, substantially as set forth.

95

3. An improved steam-boiler comprising a 100 suitable casing or setting having an inclined rear wall provided with a draft-passage 22, a bridge-wall having a draft-opening below the grate, an upper and a lower inclined water-chamber extending, respectively, above and 105 upon the bridge-wall and across the upper part of the casing or setting, a number of fire-tubes connecting and extending through the chambers, a corresponding number of water-tubes, each surrounding one of the fire-tubes 110 and opening through the top of the lower chamber and the bottom of the upper chamber, a water-inlet pipe entering the front side of the lower chamber, and a blow-off pipe connected also to said side of the lower chamber, 115 the said pipes extending forwardly through the fire-chamber beneath the grate, substantially as set forth.

115

In testimony whereof I affix my signature in presence of two witnesses.

FRANK SOMMER.
